Inventor
EMANUEL CARLSON

By his Attorney

Morris Spindstein

UNITED STATES PATENT OFFICE.

EMANUEL CARLSON, OF YONKERS, NEW YORK.

DEVICE FOR OPENING BOX COVERS.

1,409,926.

Specification of Letters Patent. Patented Mar. 21, 1922.

Application filed April 8, 1920. Serial No. 372,254.

To all whom it may concern:

Be it known that I, EMANUEL CARLSON, citizen of the United States, and resident of the city of Yonkers, in the county of West-
5 chester and State of New York, have invented certain new and useful Improvements in Devices for Opening Box Covers, of which the following is a specification.

This invention relates to devices for open-
10 ing box covers such as air tight fitting cov-
ers of tin boxes.

One of the objects of this invention is to provide a device of this type characterized by simplicity of construction and efficiency
15 of action in a high degree.

Another object is to provide a practical device of the above type in which the parts may be secured to the box or box cover without piercing through the material thereof.

20 A further object of this invention is to provide a device of the above type which may be applied to any box having a close fitting cover and which may be easy and simple of manipulation.

25 Other objects will in part be obvious and in part pointed out hereinafter.

In the drawing in which is shown one of the various possible illustrative embodiments of this invention,

30 Fig. 1 is a perspective view of a box pro-
vided with an embodiment of this invention with the opening device in the process of being operated;

Fig. 2 is a cross-sectional view thereof cut
35 along line 2—2 of Fig. 1;

Fig. 3 is a detailed broken away vertical elevation in section showing the means for attaching the operating member of the device to the cover; and

40 Fig. 4 is an end elevation of a box and cover viewed to show this operating member.

Referring in detail to the drawing, 10
represents the box and 11 the cover therefor. The body of the box is provided with an an-
45 nular offset or flange 12 of comparatively substantial width. Secured to the cover is an operating member 13 comprising a handle 14 whereby it may be manipulated by the hand of the user as shown in dotted lines in

50 Fig. 1, and extending from either end is a lever opener 15, in the form of an extension formed with a head portion 16 adapted to engage and press down against the annular flange 12, to separate the box from the cover
55 when the handle is lifted as will be readily understood. Any suitable means may of

course be applied for securing the lever openers and handle to the box cover. In the embodiment of the invention shown in the drawing, the handle and lever openers are 60 pivoted on the cover by means of a depression 17 in which is fulcrumed a straight pivot portion 18 intermediate the lever opener extension and handle and integral therewith. To maintain the operating mem- 65 ber in pivoted position on the cover, a holding strip 19 is soldered or otherwise secured over the pivot portions 18, and may fill in the depressed portion 17 of the cover so as to be flush with the top thereof as shown, 70 to leave the cover smooth and facilitate stacking of the boxes. If desired, a ridge or depression 20 may be formed in the cover to receive the handle 14 so that the latter may be flush with the cover and the depres- 75 sion 17 may be part of this ridge as will be readily understood.

As will be readily seen, the operating member 13 may be secured to the bottom of the box instead of the cover if desired and 80 the flange 12 formed on the cover instead of on the body of the box and the operation thus reversed to separate the cover from the box. It will be noted that in thus securing the operating member to the cover or box in 85 the manner hereinbefore described and in thus forming either of the latter with the flange to co-operate therewith, there is avoided the piercing of the material of these members for the purpose of securing the 90 opening device.

It will also be clear that instead of the flange 12 either on the box or on the cover, projecting portions may be provided on one of these members and disposed in operative 95 relation to the lever openers 15 and the box may be then opened by the same operation as hereinabove described and explained.

As various other possible embodiments might be made of the above invention and as 100 various changes might be made in the embodiment above set forth, it is to be understood that all matter herein set forth or shown in the accompanying drawings is to be interpreted as illustrative and not in a 105 limiting sense.

It will thus be seen that there is provided apparatus in which the several objects of this invention are achieved and which is well adapted to meet the conditions of practical 110 use.

Having thus described my invention, I

claim as new and desire to secure by Letters Patent:—

A box, a cover therefor, an annular flange on one, the other having a depression, an 5 operating member comprising a handle adapted to normally rest in said depression, pivot means extending from said handle adapted to be positioned in said depression, lever arms extending from said pivot means

adapted to act against said flange, and 10 means disposed over said depression for holding said pivot means in position therein, said means being flush with the surface of the member having the depression.

Signed at New York city, in the county of 15 New York and State of New York this 6th day of April, A. D. 1920.

EMANUEL CARLSON.
